ABSTRACT: The present invention relates to a multicolor pick change device for weaving machines of the type in which weft is drawn from a supply located outside a shed of a fabric being woven, with at least two thread feeders with thread eyelets that guide the weft threads connected to the selvage from the supply cones and are employed to feed the weft thread selectively in the color to be inserted in the shed to a point where it can be picked up or taken over by a weft inserting member.

MULTICOLOR PICK CHANGE DEVICE FOR WEAVING MACHINES

BACKGROUND OF THE INVENTION

In pick change devices for this type of weaving machine and already known in the art the delivery motion of the thread feeders is obtained by pneumatic actuation. It involves the disadvantage that the rate of operation of the weaving machines is limited by the mode of operation of the pressure cylinders and that it requires costly equipment such as numerous control valves and a compressor or other source of air pressure.

Again, pick change devices are known in which the drive of the delivery motion of the thread feeders is effected by mechanical or electromagnetic means which, however, overlap the weft threads in readiness in such a manner owing to their design that operating the machine is rendered difficult.

It is an object of the present invention to provide a device which is free of the said disadvantages, that is, which will be simple in design, will function in a purely mechanical fashion so that one need not depend upon pneumatic or electromagnetic units. A further object is that of devising mechanism by which a weft feeder may be projected or withdrawn at and for the proper time period in the cycle and also selection made and stored to govern the next following change but during at least part of the time period in which the then feeding weft is in action.

SUMMARY OF THE INVENTION

In order to insure reliable pickup of the weft thread by a carrier, it is of particular significance that the weft threads be conducted, with the greatest possible accuracy, to a common point of transfer by all thread feeders.

The invention is accordingly characterized in that each of the thread feeders can be swung about an axis of rotation substantially parallel with the thread eyelet, that the ends of the thread delivery members carrying the thread eyelets arranged in a plane substantially normal to the run of the thread are so cranked or offset that each thread feeder end and its associated eyelet can be swung to a weft thread feeding or pickup point common to all eyelets.

The invention also comprises a simple and positive means to control the feeders in a properly timed, and noninterfering relationship, and further, to govern their actuation from a dobby, jacquard or other pattern means so that the dictates of that pattern shall be stored and then made effective at the proper point in the cycle.

BRIEF DESCRIPTION OF THE DRAWINGS

FIG. 1 is a view of the thread feeders according to this invention, and a cam drive shown in operative position for imparting motion to the feeders;

FIG. 2 is a schematic view of the arrangement according to the invention of thread selection levers, control shafts and transfer members from the card control, the cam drive being represented in its idle position and the weaving machine frame so shown in partial section that the thread feeders cannot be seen;

FIG. 3 is a section along line III-III in FIG. 2 with the arrangement of the selection lever when the driver is operative and shown in plan view;

FIG. 4 is a similar section along line III-III in FIG. 2 but with the arrangement of the selection lever when the driver is inoperative;

FIG. 5 is a section along line V-V in FIG. 2 with the spring storage arrangement shown in plan view;

FIG. 6 is a section along line VI-VI in FIG. 2 with the locking lever arrangement shown in plan view;

FIG. 7 is a view of the locking lever arrangement in locking position;

FIG. 8 is a view of the locking lever arrangement with the said lever latched out of locking position; and

FIG. 9 is a part plan view of the arrangement of the thread feeders with their thread eyelets.

DESCRIPTION OF THE PREFERRED EMBODIMENT

As seen in FIG. 1, four thread feeders 1 through 4 are rotatably arranged on bolts 6 through 9 attached to the weaving machine frame and so disposed that thread eyelets 1', 3', 4' provided in these thread feeders in inoperative position are positioned side by side and keep the weft threads not involved in the weaving process away from the range of operation of a weft insertion member (not shown). The thread eyelets 1'-4' move on an arcuate path toward the thread feeding point 82 located at substantially one point, here that occupied by thread eyelet 2' of feeder 2.

In order to ensure this, the ends of the thread feeders 1-4 provided with the eyelets 1'-4' are laterally offset or cranked in such a manner FIG. 9, that each of the eyelets is located, in active position of any associated thread feeder, substantially at the thread feeding point 82. The feeder 1 is thus disposed in a single vertical plane. Feeders 2, 3 and 4 are progressively cranked at their ends to an extent to bring their ends into the same plane of feeder 1. Pivots 6-9 are so arranged that eyelets 1'-4' swing down to the point 82. The thread feeders 1-4 are kept in idle position resting against the stops 14-17 arranged on a part 5 of the weaving machine frame, by the action of springs 10-13. The feed motion is effected by the pressure of one of the associated drivers 22-25, one for each thread feeder, the said pressure being exerted on the feeders' lever arms 18-21, FIGS. 3 and 4 also, the said drivers being in their turn individually rotatable on a common spindle 25a on slide 26. The slide 26 is guided by a slot 27 engaging a roller 29 arranged on a fixed bolt 28 on a lever 32 arranged on a stud 31 and connected with an articulating bolt 30. It is moved, through connecting rod 34 pivoted at 33 and 81, and a roller lever 35, by cam 37 which is rigidly attached to a shaft 36 and which turns at one-half the weaving rate, that is, so that a feeder change may be made at each pick, if desired. Of the drivers 22, 23, 24, or 25, that one has its tongue 22'-25' located in the range of operation of the lever arms 18-21 of a thread feeder (FIG. 3) as is associated with the weft color to be inserted in the shed. The other drivers are located outside the range of action of the thread feeders (FIG. 4).

A switching movement is imparted to the drivers 22-25 by selecting levers 38-41 (FIG. 2), engaging their slots 22"-25"; the said levers can be individually rotated about a common stationary shaft 42 and are forced, by the action of springs 43-46 against the control corners or edges of sectors 47' and 48' (FIG. 4) of control shafts 47 and 48 supported at 5' and 5", (FIG. 2), and rotatable about their longitudinal axes.

The control shafts 47 and 48 individually and selectively assume one of two positions which can be controlled by a card unit or a dobby or jacquard machine (not shown) so that the two shafts together may assume four possible positions. In one possible position the control edges of the two control shafts 47, 48 are withdrawn and enable the selection lever 38, 39, 40 or 41 to assume the operative position according to FIG. 3 under the action of spring 43, 44, 45 or 46. In the other three positions of the control shafts 47 and 48, either one or two control edges project and prevent the selection lever 38, 39, 40 or 41 FIG. 4, from assuming operative position. The control edges of the control shafts 47 and 48 are staggered, relative to the two control shafts, for each of the four selection levers 38-41 (FIG. 2), so that another selection lever assumes the operative position according to FIG. 3 in any one of the four possible positions of the control shafts 47 and 48.

The transmission of motion from the card control attachment (not shown) to the control shafts 47 and 48 is effected at the time when one of the thread feeders 1, 2, 3 or 4 is extended (lowered) and, guided by its thread eyelet 1', 2', 3' or 4', its weft thread is being inserted in the shed. As the extended thread feeder must then remain immobile in its position, rotation of the control shafts 47 and 48 is prevented by locking levers 49 and 50 projecting from them which come to rest, via their arms 49' and 50', (FIGS. 2 and 5) against lugs 51 and 52 projecting from an arm extending from slide 26 when the latter is in the position corresponding to an extended

thread feeder as shown in FIG. 1. The motion of the card control attachment is then stored in torsion springs 53 and 54 which rest with both ends 53' and 54' on an extension 49" and 50" of the fixed levers 49 and 50 and on an extension 55' and 56' of levers 55 and 56 freely rotatable on the control shafts. This storage is operative for its intended purpose when the downward movement of slide 26 on the return of a thread feeder into its idle position causes the fixed levers 49 and 50 to be released by the lugs 51 and 52 and the control shafts 47 and 48 rotate under the action of the tensioned torsion springs 53 and 54 so as to move the necessary selection lever with the associated driver into operative position.

The color selection device described could, in a manner not shown, be provided, in stead of with two control shafts 47 and 48 for four colors, only with one control shaft for two colors or with three or more control shafts for six, eight or more colors.

Transfer of motion from the card control attachment to the levers 55 and 56 in the one direction is effected positively by means of wire ropes or cords 58 and 59 guided by rollers 57 and, in the other direction, by tension springs 60 and 61 attached to the machine frame 5 and to arms 55" and 56", FIGS. 2 and 6. The wire ropes may be replaced by other means of transmission, e.g. connecting rods and levers. To sum up, wire cords 58, 59, or one of them, may pull levers 55", 56" and rotate levers 55, 56 and their extensions to tension a spring 53, 54, as the case may be. Nothing further happens until lugs 51, 52 release arms 49', 50' whereupon the stored tension in the springs rotates the shafts 47, 48 to complete the pattern selection for the drivers and change the feeders as governed by cam 37.

In positive open shed dobbies where partial intermediate lowering of the upper shed occurs during the change of shed, the transmission of motion to the levers 55 and 56 is transmitted, via curved levers 65 and 66 rotatably arranged on a fixed shaft 64 and connected to the dobby by means of connecting rods 62 and 63, to roller levers 68 and 69 rotatably arranged on the fixed shaft 67 and connected to the wire ropes 58 and 59. The curved portions 65' and 66' are preceded by radially curved contours to ensure that the control motion desirable for the partial intermediate lowering of the shafts is not transferred to the multicolor pick change device. The curved levers 65 and 66 may also be replaced by slides. The contour of the cam ends of the levers is such that the undesirably ineffective motion does not affect the levers 68, 69 but further motion does. If one of the thread feeders 1, 2, 3 or 4 has projected to the thread pickup point, a locking lever 71, FIGS. 7 and 8, pivoted on a fixed bolt 70 moves, under the action of a spring 78, its shoulder 71' underneath the lifted slide 26, FIG. 7. This will hold the said slide and, together with it, the thread feeder, in their position as long as picks of the same color are inserted in the shed. The cam 37 keeps on rotating and moves with its flat or inactive portion 37', past a roller 72 with some play. When the card of the card control attachment indicates a change of color inserted, the wire cords 58 and 59 cause one or both of the levers 55 and 56 to perform an angular movement.

During that movement, the latter press their arms 55" and 56" against the projections 73 and 74 of the lever 76 arranged on a pivot 75. This causes the lever with its arm 76' to move the locking lever 71 away from the slide 26 which is then free to move in the downward direction. This downward motion of the slide is effected by the action of a spring 77, FIG. 2, when the cam 37 has continued its rotation sufficiently for the cam portion 37' to permit the roller 72 and arm 35 to swing to the right, FIG. 1. Up to that phase, a pawl 80 arranged on a bolt 79 and under the action of the tension spring 78, holds the locking lever 71 open by its nose 80', FIG. 8. Simultaneously with the downward movement of the slide 26, the appropriate thread feeder 1, 2, 3 or 4 is moved back into its idle position by the action of the spring 10, 11, 12 or 13 and the pawl 80 is forced into its initial position when struck by the slide 26, FIG. 2, where it releases the nose 80'.

In operation a stored selection will cause the desired selecting lever 38-41 to set its driver 22-25, as the case may be, and upward motion of slide 26 will move the corresponding feeder to position for its weft to be taken by the carrier.

Instead of arranging the cranks of the thread feeders as shown in the embodiment shown, the said cranks may also be arranged in a reverse or different order.

With the present invention the speed of the weaving machine is not limited by the pick change device thanks to the fully mechanical drive of the thread feeders and the small masses moved. The arrangement of the pick change device behind the weft threads in a position of readiness where only the arms of the thread feeders provided with eyelets come into their area, ensures the maximum possible clarity of design.

This disclosure of a preferred embodiment of the invention is to be interpreted as illustrative of forms the invention may take and modifications will readily occur to those skilled in the art. The invention is not to be restricted except by the scope of the appended claims wherein the novel features desired to be protected by Letters Patent are set forth:

I Claim:

1. A multicolor pick change device for weaving machines with at least two thread feeders, a thread eyelet for each feeder which guides a weft thread being drawn from supply cones arranged outside the shed of a fabric being woven and which can move the weft thread of the color to be inserted in the shed to a point of pickup where it can be engaged by a weft inserting carrier, characterized in that, spaced and parallel pivots are provided, one for each of the thread feeders and so positioned and directed that each thread feeder swivels about its own axis of rotation substantially parallel with the axis of its thread eyelet, ends of the thread feeders being arranged in a plane substantially normal to the direction of the threads and in which ends said thread eyelets are fixed, some of said feeder ends also being laterally offset into a plane of a companion feeder end so that each of the feeder ends and its eyelets can be swung into an operative position to a thread pickup point which is common to all thread feeding eyelets.

2. A multicolor pick change device for weaving machines with at least two thread feeders, a thread eyelet for each feeder which guides a weft thread being drawn from supply cones arranged outside the shed of a fabric being woven and which can move the weft thread of the color to be inserted in the shed to a point of pickup where it can be engaged by a weft inserting carrier, characterized in that, spaced and parallel pivots are provided, one for each of the thread feeders and so positioned and directed that each thread feeder swivels about its own axis of rotation substantially parallel with the axis of its thread eyelet, ends of the thread feeders being arranged in a plane substantially normal to the direction of the threads and in which ends said thread eyelets are fixed, some of said feeder ends also being laterally offset into a plane of a companion feeder end so that each of the feeder ends and its eyelets can be swung into an operative position to a thread pickup point which is common to all thread feeding eyelets, and means for moving said thread feeders to and from weft feeding position which includes springs to move them from feeding position and a sliding drive member, drivers pivoted on said sliding drive member movable to an active position in which they engage a part of the thread feeders and to an inactive position in which they do not affect said feeders, a cam for moving said drive member at each pick of the weaving machine at which a weft change is to be effected, means to latch the drive member in a position to hold a feeder active and pattern controlled means including pivoted selector levers articulated with their drivers, one for each driver, to determine which driver shall cause a feeder to present its weft to the carrier.

3. Mechanism as defined in claim 2, wherein the movable member comprises a slide, a shaft on said slide on which said drivers are pivoted and the cam for moving the slide acts to set the slide in position to cause a feeder to introduce its particular weft, and spring means to return the slide to release one feeder and pick up another when permitted to do so by said cam and the pattern control.

4. Mechanism as defined in claim 2, wherein the selecting means for the drivers comprises a means for effecting and storing pattern indications for change, said means also unlatching the said drive member.

5. Mechanism as defined in claim 4, wherein said means for effecting and storing pattern indications comprises levers to be selected, at least one shaft and lever positioning means thereon for each lever, a locking means for the shaft, an arm fixed to the shaft, another arm freely rotatable on the shaft and movable by a pattern selecting means, a spring connection between the said arms which is tensioned at selection indication and which acts to set the shaft and levers in accordance with that stored selection when the locking means for the shaft

is released.

6. Mechanism as defined in claim 5, wherein said locking means comprises an arm extending from the driver carrying member, lugs on the arm and projections from the shaft engageable by said lugs when the driver carrier member is released and moves to one extreme position under the influence of its return spring.

7. A pick change device according to claim 4, wherein the means for effecting and storing pattern indications is effected via certain levers having a cam contour which comprises a strokeless portion and a curved cam portion.
